FLASK FILLING APPARATUS

Walter E. Naylor, Chicago, Ill., assignor to The
Beardsley & Piper Company, Chicago, Ill., a
corporation of Illinois

Application August 2, 1937, Serial No. 156,861

10 Claims. (Cl. 22—36)

The present invention relates generally to apparatus for filling flasks with moulding sand. More particularly the invention relates to that type of apparatus which is designed for use in a foundry and comprises an assembly in the form of a rotary projector and an electric motor for driving the projector and causing it to form wads of sand and project the latter downwardly into a subjacent flask, a mounting whereby the assembly of projector and motor is suspended or supported so that it is universally movable to a limited extent, and power driven means for moving the assembly over the flask so as to cause it to fill the latter with sand.

15 One object of the invention is to provide a flask filling apparatus of this type which is generally an improvement upon, and has greater capabilities of use than, previously designed apparatus of the same general character and for the same purpose by reason of the fact that the power driven means for moving the assembly of projector and motor is so designed that it is adapted in connection with a flask filling operation to move the assembly in a certain course 20 or path over the flask for a predetermined length of time and then automatically to move the assembly in a different course for a predetermined length of time in order to effect filling of all portions of the flask without manual manipulation or control.

Another object of the invention is to provide a flask filling apparatus of the type and character under consideration in which the power driven means for moving the assembly comprises a 25 motor actuated mechanism for swinging or moving the assembly in the one course and a second or independent motor actuated mechanism for moving the assembly of projector and motor in the other or different course.

40 Another object of the invention is to provide a flask filling apparatus of the last mentioned character in which each of the motor actuated mechanisms constituting the power driven means for automatically moving the assembly over the flask includes a variable speed reducing unit 45 whereby the speed of movement of the assembly may be controlled or adjusted at will.

A further object of the invention is to provide a flask filling apparatus of the type and character heretofore mentioned in which the motor actuated mechanisms are so designed and arranged that they may, if desired, be conjointly operated so as to effect a compound movement of the assembly.

55 A still further object of the invention is to

provide a flask filling apparatus which is generally of a novel character.

Other objects of the invention and the various advantages and characteristics of the present flask filling apparatus will be apparent from a 5 consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side view of a flask filling apparatus embodying the invention;

Figure 2 is a plan view illustrating in detail the design and arrangement of the motor actuated mechanisms constituting the power driven 20 means for automatically moving the assembly of projector and motor for flask filling purposes;

Figure 3 is a vertical transverse sectional view 25 on the line 3—3 of Figure 1;

Figure 4 is an end view of the frame which forms part of the mounting for supporting the assembly of projector and motor so that it is universally movable to a limited extent;

Figure 5 is a fragmentary perspective of the 30 upstanding member above the assembly of projector and motor and the operating connections between said member and the motor actuated mechanisms, illustrating in detail the manner in which said connections are connected to the member; and

Figures 6 and 7 are diagrammatic views of the 35 motor actuated mechanisms and the electrical control system therefor, illustrating the manner in which the mechanisms operate to move the assembly of projector and motor.

The apparatus which is shown in the drawings constitutes the preferred form of the invention and is adapted primarily for use in a foundry or like establishment. It operates, as 45 hereinafter described, to fill a subjacent flask *f* with moulding sand and comprises as the main parts thereof a supporting structure *3*, a wad forming and swinging assembly in the form of a rotary projector *9* and an electric motor *10*, a 50 mounting *11* for suspending the assembly from the supporting structure so that it is universally movable to a limited extent, and power means *12* for automatically moving the assembly of projector and motor so as to cause the projector in 55

connection with a flask filling operation to fill all portions of the flask *f* with wads of sand.

The supporting structure *8* consists of a rectangular horizontally extending platform forming frame *13*. This frame serves as a support for the mounting *11* and the assembly moving means *12*. It is supported in an elevated position by legs (not shown) and embodies a pair of laterally spaced side beams *14*, lower cross-beams *15*, and upper cross-beams *16* and *17*. The side beams *14* are channel shaped in cross-section and are supported in laterally spaced and parallel relation by way of the lower and upper cross-beams. The lower cross-beams *15* are four in number and are arranged in laterally spaced pairs at the ends of the side beams. The upper cross-beams *16* are two in number and extend between the central portions of the side beams. They are channel-shaped in cross-section and are arranged in laterally spaced relation. The upper cross-beams *17* are two in number and are located at one end of the frame *13*. They are spaced laterally apart, as shown in Figures 1 and 2 and like the cross-beams *16* are channel shaped in cross-section.

The projector *9* is of the rotary variety and corresponds in design and operation to that which is shown in and forms the subject matter of a United States Letters Patent No. 2,092,329 granted to Walter F. Piper, September 7, 1937. It operates to form wads of moulding sand and to sling the wads downwards in rapid succession into the flask *f* and comprises a cylindrical casing *18*, a hopper *19* at one end of the casing, a blade-equipped rotor (not shown) in the casing, and a downwardly extending elongated discharge tube *21*. The hopper *19* serves to deliver sand from an overhead sand supply (not shown) into the casing and the rotor *20* operates during drive of the electric motor *10* to form the sand in the casing into wads and sling the wads downwards through the discharge tube *21* into the flask *f*. The motor *10* is fixed to and coaxially positioned with respect to the other end of the projector casing *18*, that is, the end which is opposite to the hopper *19*, and embodies an armature shaft which projects into and is keyed or otherwise fixedly secured to the hub of the blade equipped rotor *20* of the projector.

The mounting *11* for suspending or supporting the assembly of projector and motor for limited universal movement, is the same in design and construction as that which is shown in and forms the subject matter of an application for United States Letters Patent filed by me, January 28, 1937, Serial No. 122,700. It comprises a frame *22* and a yoke *23* and underlies the platform forming frame *13* of the supporting structure *8*. The frame *22* is rectangular and is disposed a small distance beneath said frame *13*. It surrounds the assembly of projector and motor and consists of a pair of side members *24* and a pair of end members *25*. The side members are positioned in parallel relation with the side beams *14* of the frame *13* and extend alongside of the projector and motor assembly. They are formed of pipes and are held in laterally spaced and parallel relation by way of the end members *25*. The latter are yoke-shaped, as shown in Figure 4, and have upwardly facing semicircular seats *26* at their ends in which the ends of the side members *24* are secured. The mounting frame *22* is suspended at the ends thereof from the frame *13* of the supporting structure *8* by way of a pair of base plates *27*, hangers *28*, and a pair of rubber blocks

29. The base plates underlie the central or arched portions of the yoke-shaped end members *25* and are secured to the lower ends of the hangers *28*. The latter are four in number and are arranged in pairs at the ends of the mounting frame *22*. They straddle the end members *25* and are secured to and depend from the lower cross-beams *15* of the frame *13* of the supporting structure. The rubber blocks *29* are disposed between the base plates *27* and the central or arched portions of the yoke-shaped end members *25* and form pivotal connections whereby the frame together with the assembly of projector and motor is permitted to rock laterally. They are located in substantially the same plane as the common axis of the projector and motor and are suitably secured against displacement with respect to the base plates and said end members. The yoke *23*, which together with the frame *22* constitutes the mounting *11*, is disposed substantially midway between the yoke-shaped end members *25*. The ends of the yoke *23* are pivotally connected to the side members *24* by rubber blocks *30* and a pair of bracket plates *31*, and the central portion of the yoke is flat, as shown in Figure 3, and overlies and is welded or otherwise fixedly secured to a plate *32* which is fixed to the top portions of the casings of the projector and motor. The bracket plates *31* are fixedly secured to the central portions of the side members *24* of the frame *22* and support the rubber blocks *30*. The latter underlie the ends of the yoke *23* and permit the assembly of projector and motor to tilt up and down about a transverse axis at right angles to the axis about which the frame *22* is free to rock laterally. The blocks *29* and *30* are positioned substantially in the same plane and the two axes substantially intersect one another. By reason of the fact that the assembly of projector and motor can rock laterally and also tilt vertically it is movable universally. The transverse and longitudinal axes for the assembly are so arranged that they intersect one another at substantially the center of mass of the assembly and hence the assembly may be moved in connection with a flask filling operation with a minimum amount of force.

The power means *12* for automatically moving the projector over the flask *f* in order to cause it to fill all portions of the latter, consists of a motor actuated mechanism *33* and a motor actuated mechanism *34*. These two mechanisms, as hereinafter described, operate, when successively or alternately operated, to move the assembly of projector and motor in different courses and when concurrently or conjointly operated to effect a compound movement of the assembly.

The mechanism *33* is located above the frame *13* of the supporting structure *8* and consists of an electric motor *35*, a variable speed reducing unit *36*, a gear box *37*, a driving disk *38*, and an arm *39*. The motor *35* is fixed to a carriage *40* on a bed structure *41*. The latter, as shown in Figures 1, 2 and 3, is mounted on a plate *42* which extends across and is supported by one of the cross-beams *16* and one of the cross-beams *17*. The variable speed reducing unit *36* consists of a pair of oppositely facing cone shaped disks *43* and *44*, an endless belt *45*, and a pulley *46*. The disk *43* is mounted on one end of the armature shaft of the electric motor *35* and embodies an elongated hub *47*. The latter is splined to the armature shaft so that it is driven by the latter and is free to move longitudinally to and from the motor *35*. The disk *44* is positioned in op-

posed relation to the disk 43 and is fixed to the armature shaft. The disk 43 is urged towards the disk 44 by means of a compression spring 48 which encircles the hub 47 and extends between the disk 43 and a washer on the outer end of the armature shaft. The endless belt 45 extends between the disks 43 and 44 and the pulley 46 and serves to drive the pulley from the disks. One end of the belt encircles the armature shaft of the motor 35 and fits between and engages the conical faces of the two disks and the other end of the belt extends around the pulley 46. The compression spring 48 because it serves to urge the disk 43 towards the disk 44 causes the side faces of the belt to engage the conical faces of the disks and serves automatically to take up for any wear. The carriage 40 is mounted on the bed structure 41 so that the motor 35 is movable bodily to and from the pulley 46. Sliding movement of the carriage with respect to the bed structure is controlled by means of a screw shaft 49 which extends through an internally threaded socket 50 on the bed structure and is confined at one end thereof in a bearing (not shown) in the carriage so that it is free to rotate but is held against axial displacement. A hand wheel 51 is connected to the screw shaft 49 and permits the latter to be turned. When the hand wheel is rotated in one direction, the carriage 40 together with the motor 35 is moved away from the pulley 46. When the wheel is turned in the reverse direction the carriage together with the motor is shifted towards the pulley. When the motor 35, as the result of manipulation of the hand wheel 51 is shifted away from the pulley the end of the belt 45 which encircles the armature shaft of the motor forces the disks apart and in a sense contracts itself around the armature shaft. As a result of this so called contraction the pulley 46 is caused to rotate at a relatively lower speed. When the motor 35 is shifted or moved towards the pulley 46 slack is caused to form in the belt and this slack is taken up as the result of the compression spring 48 forcing the disk 43 towards the disk 44 and thus increasing the diameter of the end portion of the belt which encircles the armature shaft of the motor 35. By increasing the diameter of such end portion of the belt the ratio of the drive between the two disks and the pulley 46 is increased and the pulley is driven faster or at an increased speed from the disks. By adjusting the motor to and from the pulley, any desired speed reduction with a given range may be effected. The gear box 31 of the mechanism 33 is mounted on a plate 52 on the upper cross-beams 17 of the frame of the supporting structure and consists of a housing 53, a horizontally extending shaft 54, a vertically extending shaft 55, and speed reducing gearing (not shown) in the housing and serving to connect the shaft 55 for drive by the shaft 54. The shaft 54 is journaled in bearings in the housing 53 and extends into and is fixed to the hub of the pulley 46. The shaft 55 is journaled in the housing 53 and carries at its upper end the driving disk 38. The arm 39 extends substantially horizontally and is pivotally connected at one end thereof to an upstanding pintle 56 on the outer margin of the disk 38. The other end of the arm is pivotally connected to a rod 57 which extends upwardly from the central portion of the yoke 23 and is fixedly secured to such portion by way of a bracket 58. When the motor 35 of the mechanism 33 is operated, the disk 38 is driven or rotated as a result of drive by the variable speed

reducing unit 36 and the shafts 54 and 55 of the gear box 31. During rotation or drive of the disk 38 the arm 39 is shifted back and forth and through the medium of the upstanding rod 57 tilts the assembly of projector and motor up and down and causes the discharge tube 21 to move in substantially an elliptical course over the flask 7. The arm 39 constitutes the driving connection between the motor actuated mechanism 33 and the assembly and includes a sleeve-like part 59 whereby the distal end portion thereof, that is, the portion which is connected to the upper end of the rod 57 is free to tilt vertically to a small extent. The mechanism 34, like the mechanism 33 is located above the frame 13 of the supporting structure 8. It is similar in design and construction to the mechanism 33 and consists of an electric motor 60, a variable speed reducing unit 61, a gear box 62, a driving disk 63, and an arm 64. The motor 60 is mounted on a carriage 65 and serves to drive the disk 63 through the medium of the variable speed reducing unit 61 and the gear box 62. The carriage 65 is slidably mounted on a bed structure 66 and it, together with the motor is controlled as far as sliding movement thereof is concerned by way of a handle equipped screw shaft 67. The bed structure 66 is mounted on a plate 68 on the upper cross-beam 16 of the frame 13. The variable speed reducing unit 61 is similar in construction and design to the unit 45 of the mechanism 33 and consists of a pair of opposed cone shaped disks 69 and 70, an endless belt 71, and a pulley 72. The gear box 62 comprises a horizontally extending shaft 73, and a vertically extending shaft 74 and underlies the driving disk 63. The shaft 73 carries and is driven by the pulley 72 and is connected by gearing to drive the vertical shaft 74. The upper end of the shaft 74 is fixedly connected to the driving disk 63 and the latter, as shown in Figure 2, embodies an upstanding pintle 75 on its marginal portion. The motor 60 and the speed reducing unit 61 are positioned at right angles to the motor and speed reducing unit of the mechanism 36 and the gear box 62 is located at one side of the frame 13 of the supporting structure, as shown in Figure 2. The arm 64 extends substantially at right angles to the arm 39 and is pivotally connected at one end thereof to the pintle 75. The other or distal end of the arm 64 is pivotally connected to the upper end of the upstanding rod 57. When the motor 60 is operated the disk 63 is driven through the medium of the speed reducing gearing 61 and the gear box 62 and it, in turn, operates by way of the pintle 75 to move the arm 64 back and forth. When the arm 64 is moved back and forth the assembly of projector and motor is rocked laterally and the discharge tube 21 is caused to travel or move through a substantially elliptical course at substantially right angles to the course in which the tube is moved when the assembly is moved or shifted by the motor actuated mechanism 33. The arm 64 constitutes the operating connection between the mechanism 34 and the assembly and includes a sleeve-like part 76 whereby the outer end portion thereof is permitted to swing vertically to a limited extent. When the motor actuated mechanism 33 is operated the assembly of projector and motor, as hereinbefore described, is moved back and forth in one direction, that is, throughout a certain course, and when the mechanism 34 is in operation the assembly is moved or shifted back and forth in another direction. When the two mech-

anisms 33 and 34 are conjointly operated the arms 39 and 64 effect a compound movement of the assembly. By varying or adjusting the units 36 and 61 any desired type of compound movement of the assembly may be obtained in order to effect complete filling of the flask in connection with a flask filling operation.

In addition to the supporting structure 8, the assembly of projector and motor, the mounting 10 11, and the means 12 for automatically moving the assembly for flask filling purposes, the apparatus comprises an electrical control system for controlling the motors 35 and 60 for successive or alternate operation and for conjoint movement. This system comprises a two pole double throw switch 77, a pair of normally open spring contact switches 78 and 79, a cam 80 for alternately closing the switches 78 and 79, and an electric motor 81 for driving the cam. The two 15 20 pole double throw switch 77 comprises a pair of contacts 82 and 83 at one side thereof, a pair of contacts 84 and 85 at the other side thereof, and a pivoted switch element 86. The latter comprises a pair of metallic legs 87 and 88 and an insulated crosspiece 89 between the two legs and is adapted when swung in one direction to have the legs 87 and 88 engage the contacts 82 and 83 respectively, and when swung in the other direction to have said legs engage the contacts 84 and 30 35 40 45 50 55 60 65 70 75 85, respectively. Line conductors 90 and 91 are connected to the legs 87 and 88 respectively and are adapted to have electric current from any suitable source of supply pass therethrough. The switch 78 comprises a pair of contacts 92 and 93 and is adapted to be closed by the cam 80 during drive of the latter by the electric motor 81. The contact 92 is connected by a conductor 94 to the contact 82 of the switch 77 and the contact 93 of the switch 78 is connected by a conductor 95 to one terminal of the electric motor 35. The other terminal of said motor is connected by a conductor 96 to the contact 83. When the switch element 86 is swung so that the legs 87 and 88 are in contact with the contacts 82 and 83 respectively and the switch 78 is closed, current flows through the conductor 94 and the switch 78, the conductor 93, the motor 35 and the conductor 96. The motor 35 is thus operated and effects actuation of the mechanism 33 which, as hereinbefore described, causes the assembly of projector and motor to tilt or swing up and down. The switch 79 controls the flow of current to the motor 60 of the mechanism 34. It consists of a pair of contacts 97 and 98 and is adapted to be closed by the cam 80. The contact 97 is connected to the conductor 94 by a conductor 99 and the contact 98 is connected by a conductor 100 to one terminal of the motor 60. The other terminal of the motor 60 is connected by a conductor 101 to the conductor 98. When the switch element 86 is swung so as to cause the legs 87 and 88 thereof to engage the contacts 82 and 83 respectively and the switch 79 is closed, current flows through the conductors 94 and 99 to the switch 79 and thence through the conductor 100 to the motor 60 and then by way of the conductors 101 and 96 to the contact 83. As the result of the formation of such circuit the motor 60 is caused to operate and effects actuation of the mechanism 34 which, as previously described, serves to rock laterally the assembly of projector and motor. The cam 80 is driven by the electric motor 81 by any suitable type of speed reducing gearing and is adapted during drive thereof successively to close the switches 78 and 79. One terminal of the motor 81 is connected by

a conductor 102 to the conductor 99 and the other terminal of said motor is connected by a conductor 103 to the conductor 101. When the switch element is closed, as far as the contacts 82 and 83 are concerned, current flows through the conductors 94, 99 and 102 to the motor and thence from the motor through the conductors 103, 101 and 96 to the contact 83. As the result of such flow of current the motor 81 is caused to operate and effects drive of the cam 80. When the cam 10 is driven it operates successively to close the switches 78 and 79, as hereinbefore described, with the result that the motors 35 and 60 are successively or alternately driven. In order to effect conjoint or concurrent drive of the two motors 35 15 and 60 conductors 104 and 105 are provided. The conductor 104 extends between and is connected at its ends to the contact 84 of the two pole double throw switch 77 and the terminal of the motor 60 to which the conductor 100 is attached or connected. The conductor 105 extends between and is connected at its ends to the contact 85 of the double throw switch 77 and the terminal to which the conductor 95 is connected. When the switch element 86 is swung so as to bring the legs 87 and 88 thereof into contact with the contacts 84 and 85, respectively, current flows through the conductor 104, the electric motor 60, the conductor 101, the conductor 96, the electric motor 35, and the conductor 105. As the result of such flow of current both motors are operated and the mechanisms 33 and 34 of the assembly moving means 12 are caused to effect a compound movement of the assembly. From the foregoing it is manifest that the electrical control system is such that when the pivoted switch element 86 is shifted in one direction, the motors 35 and 60 are caused to operate alternately and when the element is shifted into the other direction into a closed position as far as the contacts 84 and 85 are concerned, the motors are caused conjointly to operate.

The operation of the apparatus is as follows: When it is desired to operate the motors 35 and 60 alternately so that the assembly moving means 12 operates first to cause the assembly to move back and forth in one course and then back and forth in another course, the switch element 86 is swung so as to bring the legs 87 and 88 thereof into contact with the contacts 82 and 83, respectively. When the element is so swung the electric motor 81 for driving the cam 80 is operated as the result of establishment of the following circuit: line conductor 90; leg 87; contact 82; conductor 94; conductor 102; motor 81; conductor 103; conductor 101; conductor 96; contact 83; leg 88; and line conductor 91. As soon as this circuit is established, the cam 80 is driven by the motor 81 and operates successively or alternately to close the switches 78 and 79. When the switch 78 is closed the following circuit is set up through the motor 35: line conductor 90; leg 87; contact 82; conductor 94; switch 78; conductor 95; motor 35; conductor 96; contact 83; leg 88; and line conductor 91. Upon completion or establishment of this circuit the motor 35 sets in motion the mechanism 33 and the latter operates to tilt up and down the assembly of projector and motor. When the cam 80 during drive thereof by the motor 81 is out of contact with the switch 78, the latter opens and breaks the aforementioned circuit. Upon continued or further rotation of the cam, the switch 79 is closed. Upon closing of this switch the following circuit is established through the motor 60: line conductor 90; leg 87; contact 75

82; conductor 94; conductor 99; switch 79; conductor 100; motor 60; conductor 101; conductor 96; contact 83; leg 88; and line conductor 91. Upon completion of this circuit the motor 60 operates and sets in motion the mechanism 34 which in turn operates to rock laterally the assembly of motor and projector. When it is desired to operate the motors 35 and 36 conjointly the switch element 86 is swung so as to bring the legs 87 and 88 thereof into contact with the contacts 84 and 85, respectively. Such swinging of the switch element establishes the following circuit through the two motors: line conductor 90; leg 87; contact 84; conductor 104; motor 60; conductor 101; conductor 96; motor 35; conductor 105; contact 85; leg 88; and line conductor 91. When the motors are driven alternately the speed of swing of the assembly may be controlled by varying or adjusting the variable speed reducing units 36 and 61. When the motors 35 and 60 are driven conjointly or concurrently the compound movement of the assembly may be changed or varied as far as character is concerned by adjusting the aforementioned variable speed reducing units. The motor 10 is driven at the same time the motors 35 and 60 are operated and causes wads of sand to be projected downwards into the flask *f* during movement of the assembly. By adjusting or properly controlling the assembly moving means 12, the assembly may be controlled so that it operates without manual manipulation to fill all portions of the flask *f*.

The herein described flask filling apparatus is comparatively simple as far as construction is concerned and hence may be manufactured at a low and reasonable cost. It is entirely automatic as far as operation is concerned and is adapted primarily for use in filling flasks of uniform design on an endless conveyor which serves to bring the flasks successively into range of the discharge tube 21 of the projector 9.

The invention is not to be understood as restricted to the details set forth, since these may be modified within the scope of the appended claims, without departing from the spirit and scope of the invention.

Having thus described the invention, what I claim as new and desire to secure by Letters Patent is:

50 1. An apparatus of the character described comprising in combination a supporting structure, a motor driven projector for slinging mould forming material into a subjacent flask, a mounting between the projector and the supporting structure for supporting said projector so that it is movable over the flask, and power driven means for moving the projector automatically first in one course over the flask and then in a different course.

60 2. An apparatus of the character described comprising in combination a supporting structure, a rotary motor driven projector adapted to form mould forming material into wads and sling the latter into a subjacent flask, means between the projector and structure for supporting said projector for limited universal movement over the flask, and power operated means for swinging the projector automatically first in one course over the flask and then in a different course.

70 3. An apparatus of the character described comprising in combination a supporting structure, a motor driven projector for slinging mould forming material into a subjacent flask, a pivotal mounting between the projector and the structure for supporting the projector so that it is free to

tilt up and down and rock sidewise, and power operated means whereby the projector is alternately tilted up and down and rocked sidewise.

4. An apparatus of the character described comprising in combination a supporting structure, a motor driven projector for slinging mould forming material into a subjacent flask, a mounting between the projector and the supporting structure for supporting said projector so that it is movable over the flask, and power operated means whereby the projector may be moved automatically either first in one course over the flask and then in a different course, or with a compound movement over the flask.

5. In an apparatus of the character described, the combination with a supporting structure, a motor driven projector for slinging mould forming material into a subjacent flask, and a mounting between the projector and the supporting structure for supporting said projector so that it is movable over the flask, of a motor actuated mechanism adapted during operation thereof to move the projector in one course over the flask and a second motor actuated mechanism adapted when operated to move the projector in a different course over said flask.

6. In an apparatus of the character described, the combination with a supporting structure, a motor driven projector for slinging mould forming material into a subjacent flask, and a mounting between the projector and the supporting structure for supporting said projector so that it is movable over the flask, of a mechanism including a motor and a variable speed reducing unit for automatically moving the projector in one course over the flask, and a second mechanism including a motor and a variable speed reducing unit for moving said projector in a different course over the flask.

7. In an apparatus of the character described, the combination with a supporting structure, a motor driven projector for slinging mould forming material into a subjacent flask, a mounting between the projector and the structure for supporting the projector so that it is free to swing universally to a limited extent, and an upstanding upper member projecting above and held in fixed relation with the projector, of motor actuated mechanism applied to the upper end of the member and operating automatically through said member to swing the projector in one course over the flask, and a second motor actuated member applied to the upper end of the member and operating automatically through the member to swing the projector in another course over said flask.

8. In an apparatus of the character described, the combination with a supporting structure, a motor driven projector for slinging mould forming material into a subjacent flask, a mounting between the projector and the structure for supporting the projector so that it is free to swing universally to a limited extent, and an upstanding upper member projecting above and held in fixed relation with the projector, of a mechanism including a motor, a variable speed reducing unit, and an operating connection between the unit and the upper end of the member for automatically swinging the projector back and forth in one direction over the flask, and a second mechanism including a motor, a variable speed reducing unit, and an operating connection between the unit and said upper end of the member for swinging the projector back and forth in another direction over the flask.

9. In an apparatus of the character described, the combination with a supporting structure, a motor driven projector for slinging mould forming material into a subjacent flask, and a mounting between the projector and the supporting structure for supporting said projector so that it is movable over the flask, of mechanism including an electric motor and a speed reducing unit for moving the projector in one course over the flask, mechanism including an electric motor and a speed reducing unit for moving the projector in another course over said flask, and an electrical control system for causing the electric motors to operate either alternately or conjointly.
10. In an apparatus of the character described, the combination with a supporting structure, a motor driven projector for slinging moulding material into a subjacent flask, a mounting between the projector and the structure for supporting said projector so that it is movable universally to a limited extent, and an upstanding member projecting above and held in fixed relation with respect to the projector, of a mechanism including an electric motor, a speed reducing unit, and an operating connection between the unit and the upper end of the member for swinging the projector back and forth in one course over the flask, a second mechanism including an electric motor, a speed reducing unit, and an operating connection between the unit and the upper end of the member for swinging the projector back and forth in a different course, and an electrical control system for causing the electric motors to operate either alternately or conjointly. 5 10 15
